UNITED STATES PATENT OFFICE

CHARLES D. YOUNG, OF HAVERFORD, PENNSYLVANIA

RAIL JOINT

Application filed March 9, 1931. Serial No. 521,297.

This invention relates to rail joints and more particularly to joint bars of the continuous type, the primary object of the invention, generally stated, being to provide a joint bar of the continuous type which is capable of more efficiently performing the rail supporting and clamping functions for which such bars are designed and yet which is of comparatively simple and inexpensive manufacture.

Heretofore it has been proposed to manufacture joint bars of the continuous type in a variety of cross-sectional shapes, generally characterized by the provision of three separate bearing surfaces designed to contact respectively with the underside of the rail head, the top slope of the rail flange and the underside of the rail flange. If it were possible at reasonable cost to manufacture rails and joint bars with dimensions of such accuracy that uniform contact between rail and bar might be obtained at all three of the above mentioned regions, throughout the length of a rail joint, joint bars of this character might indeed accomplish all that is claimed for them. As a matter of fact, however, rails and bars cannot, economically at least, be manufactured with such accuracy of dimensions. Rails and bars which are made in large quantities under present rolling mill practice are necessarily subject to variations in thickness and in true parallelism between surfaces, and these variations render it impossible to obtain uniform contact between three bearing surfaces on the bar, all in planes closely approaching parallelism, and corresponding surfaces on the rails. It will readily be appreciated that, as wear takes place and it becomes necessary to draw up the bars of a joint by tightening the nuts, the difficulty in maintaining uniform engagement between bar and rails at these bearing surfaces is accentuated. The result, therefore, of mill variations or irregularities in bars and rails, which have been rolled to approximate closely the desired shape but nevertheless are not strictly speaking accurately dimensioned, is that when the rail joint is assembled intimate engagement between the joint bars and rails will occur only at two

bearing surfaces rather than at three bearing surfaces; and the contemplated rail supporting function of the bars will be defeated, and this will be so even though the joint bar employed has capacity for flexure or distortion to vary the angularity between its upright member and its foot and base flanges. It may be found, for example, that, while the head of the joint bar bears effectively upon the underside of the rail head or upon the rail head fillet, to effect this engagement has caused the rail base to be imperfectly supported within the foot and base flanges of the bar—a condition which is fatal to the proper functioning of the bar.

Accordingly, the joint bar of the present invention has been designed to overcome the above recited difficulties, and this is accomplished by avoiding contact between the head of the joint bar and the rail head or rail head fillet, and by providing predetermined regions of flexure which are somewhat remote from the bearing surfaces and about which the members of the bar may be plied incident to the assembly of the rail joint, and by associating with the joint bar a supporting plate which is stiffened vertically and which bridges the ties beneath the rail joint. Joint bars of this character support the rails in vertical alignment by engagement solely at the base flanges of the rails, and whatever advantage, if any at all, is sacrificed by the non-support of the rail head, is more than compensated by the uniformity of engagement throughout the rail joint at predetermined areas of contact between the foot and base flanges of the bars and the rail bases.

Other more specific objects characterizing the rail joint structure of this invention will become more apparent from the detailed description which follows hereinafter having reference to the accompanying drawing, whereof:

Fig. I represents a side elevation of a rail joint embodying my invention.

Fig. II represents a cross section of the same, taken as indicated by the lines II—II of Fig. I.

Figs. III, IV and V represent similar views showing only the head portion of a rail and

the head portion of a joint bar, and disclosing three alternate forms which the head of the joint bar may take.

Fig. VI represents a side elevation of the joint bar of Fig. I; and,

Fig. VII represents a side elevation of a modified form of joint bar.

In the drawing, there is shown a rail of a standard cross-sectional shape, the head of the rail being designated at 1, the web portion at 2, and the base or flange at 3.

The joint bar selected for illustration is of the so-called continuous type, that is, a joint bar which includes a base flange which passes beneath the base of the rail, as contrasted with a bar the bearing surfaces of which are confined to the fishing space of a rail; and while the description of the present invention refers to a joint bar of a special or preferred shape, this particular shape is by no means essential to the invention but admits of considerable variation. Generally, the bar comprises an upright member 4, a foot flange 5 terminating in a relatively narrow downturned neck 6, and a base flange 7.

With reference to the example shown in Fig. II, it will be seen that the head portion 8 of each upright member 4 is confined to the inside of the outside vertical line of the rail head 1, and that the bolting surfaces 9 of the joint bars are in the planes of the outside surface of the rail heads. The head of each bar terminates short of the underside of the rail head 1 so that there is substantial clearance not only at the bottom slopes of the rail head but also at the rail head fillets. It is contemplated that the joint bar heads may assume a variety of alternative shapes as shown at 8a, 8b and 8c in Figs. III, IV and V, respectively, and the determining factor governing the shape of the bar head to be selected is one of moment of inertia, for the head portion of the joint bar performs no direct rail supporting function. The formation of a protuberant rib as shown at 8b and 8c serves to increase the moment of inertia of the joint bar.

The upright member 4 is relatively thick at its head portion 8, especially at the region 10 where it bears upon the web 2 of the rail, and is of gradually diminishing thickness towards the foot member 5. At the base of the bolting surface the upright member 4 is particularly thin, as indicated at x, and is spaced at some distance from the rail web, thus affording a region of flexure which permits the upright member 4 to be bodily bent with respect to the foot flange 5.

The foot flange 5 of the joint bar is relatively thick at its inner edge and of gradually diminishing thickness towards its outer edge. Intermediate the rail base fillet and the outer edge of the rail flange 3, the foot flange 5 of the joint bar bears upon a portion of the rail flange, and for this purpose the

bar is provided with a substantially flat surface 11 corresponding in inclination with the flat surface at the top slope of the rail flange. The outwardly converging top and bottom surfaces of the foot flange 5 terminate at a particularly thin portion, indicated at y, affording a region of flexure which permits the base member 7 and neck portion 6 to be bodily bent with respect to the foot flange 5.

It will be noted that there is substantial clearance at the region of flexure y between the joint bar and the rail base, it being desirable that the relative flexure of the members of the bar should occur only at regions somewhat remote from the areas of contact.

The neck portion 6 of the joint bar is relatively thin but preferably of greater thickness than the region y, and, when the bar is applied to a rail, the neck portion is spaced at a considerable distance from the edge of the rail base. Furthermore, the inside surfaces of the joint bar in the vicinity of the neck portion are preferably configured as shown in the drawing at 12, so that the margins of the rail flange adjacent to its outer edge are substantially clear of the joint bar.

The base flange 7 of the joint bar is of uniform thickness except in the vicinity of the neck portion 6, and it affords a relatively large area of contact at 13, upon which the base of the rail bears. In this connection, it will be observed that the area of contact where the bar bears upon the top slope of the rail flange is of less width than and substantially centered with respect to the area of contact where the bar bears upon the bottom of the rail flange. Accordingly, when the bar is adjusted upon the rail, the line of support remains constant and there is no chance for the bar to be improperly applied, or cocked to one side or another. The base flanges 7 of opposed joint bars are in turn supported upon a tie plate or similar foundation.

The plate 14 shown in the drawing is a two-tie joint plate having vertical ribs 15 and having irregularly shaped flanges 16 at its outside edges, which flanges are turned upward for stiffening purposes at the spaces between ties, as shown in Fig. I. Inasmuch as the base flanges 7 of the joint bars are supported upon the vertically stiffened plate 14 and are held in vise-like engagement between the base 3 of the rail and the plate 14, adequate support is provided for the rail ends and at the same time the desired flexure with in the joint bars is permitted.

It will be particularly noted that the means for fastening the joint bars together with the rail end portions gripped therebetween, which are shown as bolts 17 of the type commonly used for rail joints, are confined to the ends of the joint bars, there being no bolt holes in the central portions of the bars. By avoiding fastening bolts at the central portions of the bar, the stresses normally occur-

ring at these portions incident to the passage of heavy loads over the joint, and which tend to split the rails at their ends, are relieved, though the rail is rigidly supported on the 5 underlying joint bar flanges 7 and on the joint plate 14.

Furthermore, the joint bars of this invention may take the form shown in Fig. VII in which the foot flange 5, of the joint bar, 10 instead of being uniformly spaced with respect to the base flange 7 of the bar is vertically deflected at the center of the bar as shown at 18, while the base flange of the bar is flat throughout its length. This curvature 15 provides slight clearance at the center of the rail joint between the base 3 of the rail and the foot flange 5 of the joint bar which also acts to relieve the stresses tending to split the rails at their ends.

20 In assembling or drawing up the rail joint of this invention, such variations or irregularities in shape of the bars or rails, which occur as the result of the latitude allowed the manufacturer in making the bars to specified dimensions, or such variations or irregularities as occur as the result of wear in service, are taken care of by the regions of flexure shown at x and y which, in view of the clearance provided at the rail head, permit the bearing surfaces of the upright member 4, of the foot flange 5 and of the base flange 6 to adjust themselves to the shape of the rails incident to the tightening of the nuts on the bolts 17. Such deformation as 35 takes place when the joint bars are assembled and drawn up against the rails is confined to the regions of flexure which are, as before stated, comparatively remote from the areas of contact; and consequently the relative flexure of the joint bar members does not interfere with the maintenance of intimate engagement between the bearing surfaces of the joint bars and the rails throughout the areas at which such engagement is desired.

40 While I have described a particular rail joint, illustrating and explaining certain contemplated modifications in the form of joint bar employed therein, it will be apparent that various changes, other than 45 those herein described, may be made in the shape of the joint bar without departing from the spirit of my invention.

Having thus described my invention, I claim:

55 1. A rail joint including a continuous type joint bar formed to bear solely upon the web and flange of a rail, and having portions of reduced thickness, whereby the parts of the bar have capacity for relative flexure, and a 60 plate supporting the base flange of said joint bar and bridging a number of ties therebeneath.

65 2. A rail joint including a continuous type joint bar, comprising an upright member clear of the rail head, and foot and base

flanges having capacity for relative flexure, and a plate supporting the base flange of said joint bar and bridging a number of ties therebeneath.

3. A rail joint including a continuous type joint bar, including an upright member clear 70 of the rail head and a foot flange, said upright member having capacity for flexure with relation to said foot flange, and a vertically stiffened tie plate supporting the base flange of said joint bar and bridging a number 75 of ties therebeneath.

4. A rail joint including a continuous type joint bar, comprising an upright member clear of the rail head, a base member having a flat bearing surface contacting with the bottom of a rail flange, and a foot member with the ends thereof bearing upon the top of a rail flange, and with the center thereof deflected to provide clearance between said foot member and rail at adjoining rail ends, and a plate supporting the base member of 80 said joint bar and bridging a number of ties therebeneath.

5. A rail joint including a continuous type joint bar, comprising an upright member clear of the rail head, a base member having a flat bearing surface contacting with the bottom of a rail flange and a foot member with the ends thereof bearing upon the top 90 of a rail flange, and with the center thereof deflected to provide clearance between said foot member and rail at adjoining ends, said foot section having a relatively thin portion where it joins said base section affording 95 a region of flexure, and a plate supporting the base member of said joint bar and bridging a number of ties therebeneath.

6. A rail joint, including adjoining rail end portions, and continuous joint bars at opposite sides thereof, said bars being formed with upright members clear of the rail heads, and means for fastening said joint bars together with the rail end portions gripped therebetween, said fastening means being confined to the ends of the joint bars, and a plate supporting the base flanges of said joint bars and bridging a number of ties 100 therebeneath.

7. A rail joint, including adjoining rail end portions and continuous joint bars at opposite sides thereof, said bars comprising upright members clear of the rail head, and foot and base members with regions of flexure between said members, and means for fastening said joint bars together with rail end portions gripped therebetween, said fastening means being confined to the ends of the joint bars, and a plate supporting the base members of said joint bars and bridging a 115 number of ties therebeneath.

In testimony whereof, I have hereunto signed my name at Philadelphia, Pennsylvania, this 9th day of March, 1931.

CHARLES D. YOUNG.
